SAFETY RAZOR

Frank F. Schlattau, Los Angeles, Calif.

Application October 19, 1933, Serial No. 694,308

1 Claim. (Cl. 30—65)

This invention relates to a safety razor, and has for its object to provide, in a manner as hereinafter set forth, a razor of such class having its blade so formed with respect to the other elements of the razor to permit of the removal of the blade without completely disassembling the razor.

A further object of the invention is to provide, in a manner as hereinafter set forth, a safety razor with a reversible bifurcated blade capable of being removed from between the holder and guard elements of the razor without the necessity of completely disassembling the razor structure; with the holder element, guard element and blade having coacting parts for anchoring the blade at points adjacent the transverse medians of said elements to prevent a portion or portions of the blade shifting or the bodily shifting of the blade as an entirety relative to said elements when the razor is used, as well as for said coacting parts functioning to reinforce the blade during shaving; and with the said coacting parts on said elements not interfering with the blade during the removal of the latter.

25 A further object of the invention is to provide, in a manner as hereinafter set forth, a safety razor blade of a form capable of being used in connection with holder and guard elements of razor structures different from that as shown.

30 To the above ends essentially and to others which may hereinafter appear, the invention consists of such parts and such combination of parts, which fall within the scope of the invention as claimed.

35 In the drawings:

Figure 1 is an elevation of the safety razor.

Figure 2 is a vertical sectional view thereof.

Figure 3 is an inverted plan view of the guard element with the blade positioned thereagainst.

40 Figure 4 is a bottom view of the blade positioned against the holder element.

Figure 5 is an inverted plan view of the holder element.

Figure 6 is a top plan view of the guard element.

45 Figure 7 is a cross sectional view through the holder element, guard element and blade.

Figure 8 is an elevation of a modified form of safety razor in accordance with this invention.

50 Figure 9 is a top plan view of the blade and holder element of the modified form.

Figure 10 is an inverted plan view of the guard element of the modified form.

55 Figure 11 is a top plan view of the guard element of the modified form.

Figure 12 is a top plan view of another modified form of blade and holder element.

Figure 13 is an inverted plan view of the modified form of holder element shown in Figure 12.

Figure 14 is a top plan view of the form of 5 guard element employed with the form of blade and holder element shown in Figure 12.

Referring to Figures 1 to 7 of the drawings, the razor structure includes a handle element 1, a guard element 2, a blade 3 and a holder element 4.

The element 1 preferably will be of circular cross section, but it may be of any cross sectional contour desired. The outer end portion of element 1 is formed with a circular socket 5 of 15 suitable depth. Socket 5 is disposed axially of element 1 and opens at the outer end edge of the latter. The wall of socket 5 is upon two diameters, the smaller indicated at 6 and the larger at 7. The junction of the two diameters of the 20 wall provides a shoulder 8. The portion 6 of the wall of the socket 5 is threaded. The outer end of the portion 7 of the wall of the socket 5 is flared. The shoulder 8 provides a stop for a purpose to be referred to.

25 The guard element 2 is substantially rectangular in plan and substantially of convex curvature in cross section. The element 2 at each lengthwise edge is toothed, as at 9. Each side of element 2 is offset, as at 10 and such offset parts are 30 depressed to form grooves 11. The grooves 11 are concave, coextensive with the length of the element 2 and arranged at the base of the rows of teeth 9 at the sides of element 2. The latter is formed at its center with a square opening 12. 35 The longitudinal and transverse medians of element 2 intersect the opening 12. Between the latter and each end of element 2 is a pair of sockets. The sockets of each pair are designated 13, 40 are arranged in spaced relation and oppose each other. The sockets 13 are positioned inwardly with respect to the grooves 11.

The blade 3 consists of a substantially rectangular body of greater length and of less width than guard element 2, and when positioned on the 45 latter extends from each end thereof. The blade is formed with a slot 14 of a length slightly greater than half the length of the blade and is disposed centrally of the latter. The base of the slot is positioned between the transverse median 50 and one end and extends to and opens at the other end of the blade. The width of the furcation corresponds to the width of opening 12 in element 2. The furcation 14 forms blade 3 into what may be termed a head part 16 and a pair of 55

arms 17, 18 disposed at right angles to the latter. The blade 3 is provided with a pair of lengthwise extending cutting edges 19 of less length than the length thereof. Each corner of the blade 3 is cut out to provide the said side parts of reduced length and the said central part of greater length than said side parts, and also to form clearances for any enlargements which may be at the corners of the inner face of a guard or holder element. The clearances at one end of the blade are designated 20 and those at the other end at 21. The clearances 21 are of a different shape than the clearances 20 due to the fact that the ends of the blade are of a different form as shown.

The arms 17, 18 in proximity to their inner edges are formed with aligning openings 22, 23 respectively. The openings are positioned approximately centrally with respect to the arms. The head part 16 is formed with a pair of spaced aligning openings 24, 25 approximately centrally thereof. The openings 24, 25 align with the openings 22, 23 respectively. The openings 22, 24 are arranged adjacent one side and the openings 23, 25 adjacent the other side of the longitudinal median of the blade. The head part 16 outwardly with respect to the openings 24, 25 is formed with a keyhole-shaped opening 26 for the reception of an enlargement which may be positioned on the inner face of a holder or guard element. The opening 26 is intersected centrally by the longitudinal median of the blade. The cutting out of the corners of the blade to provide the clearances 20, also form the blade with what may be termed a finger-piece 21 capable of being gripped for the purpose of removing and inserting a blade from and between the holder and guard elements.

The holder element 4 is of substantially rectangular contour, of convex cross section and of the same length, but of less width than the guard element. Formed integral with the inner face of element 4 at the intersection of the transverse and longitudinal medians thereof is a stem 28 formed with a squared part 29 and a peripherally threaded part 30 of circular cross section having its diameter less than the width and its length greater than that of the part 29. The inner face of element 4 between its transverse median and each end is formed with a pair of lugs. The lugs of each pair align and are spaced from each other. The lugs of one pair are designated 31 and those of the other pair at 32. One lug of each pair is arranged adjacent one side and the other lug of each pair adjacent the other side of the longitudinal median of element 4. The lugs 31 and 32 are spaced from the stem 28. The element 4 is of less width than the blade 3.

When the razor structure is set up, the blade 3 is positioned upon guard element 2 in a manner whereby the base 15 of furcation will register with a side edge of opening 12 that is disposed transversely of the guard 2 and which will provide for the openings 22, 23, 24 and 25 to register with the sockets 13. The holder member 4 is then arranged in a manner whereby the stem 28 will extend through furcation 14 and opening 12, the lugs 31 passed through openings 24, 25 to seat in a pair of sockets 13 and the lugs 32 passed through openings 22, 23 to seat in the other pair of sockets 13. When the stem 28 is in the position referred to the part 29 thereof will be arranged at the inner end of the furcation 14 and extended through and beyond the opening 12. The element 1 is then screwed upon

part 30 of stem 28 until part 29 of the latter abuts shoulder 8 whereby the elements of the structure are clamped together in a position to be used. When the structure is assembled, the blade 3 extends across the grooves 11 and upon the teeth 9. Now if it be desired to remove blade 3, it can be accomplished without completely disassembling the structure, and in this connection the element 1 is partly screwed off the stem 28 to an extent to permit of removing the lugs 31, 32 clear of the blade 3. The portion 27 of the blade is then gripped and pulled laterally from between the holder and guard elements, as the furcation 14 will provide for so doing.

When the razor structure is assembled and used, the grooves 11 act as receivers for the hair and lather to prevent packing of the same under the blade.

The difference between the modified form shown in Figures 8 to 11 and that shown by Figures 1 to 7, resides solely in a different construction of guard element and blade. In the modified form referred to the handle element, guard element, blade and holder element are designated 33, 34, 35 and 36 respectively. The elements 33 and 36 are constructed in the same manner as the elements 1 and 4 respectively.

The element 34 is substantially rectangular and in cross section is of arcuate contour. The outer face of element 34 is not provided with the grooves 11 at the base of the teeth 37 arranged at its sides. The lower face of element 34 has spaced parallel lengthwise extending shoulders 38, 39 merging at their tops into the inner face of the bases of the teeth 37. Otherwise than that as stated, the construction of element 34 will be the same as 2, that is to say element 34 is formed with an opening 40 and sockets 41 corresponding in form, purpose and arrangement to opening 12 and sockets 13 respectively of element 2.

The form of blade 35 is substantially similar to that of blade 3 with this exception that the clearances 41 at the corners of blade 35 are of a different contour than those of the blade 3, and that blade 35 is not provided with an opening similar to opening 26 in blade 3. Blade 35 is formed with a furcation 42 and openings 43, 44, 45 and 46 corresponding in form, purpose and arrangement to that of the furcation 14 and openings 22, 23, 24 and 25 respectively of blade 3. The furcation 42 permits of the removal of blade 35 in the same manner as blade 3 without completely disassembling razor structure. The gripping part of blade 35 is designated 47.

The lugs on element 36 which extend through the blade 35 and engage in sockets 48 are indicated at 48. The stem of element 36 is designated 49.

The modified form of blade, holder element 60 and guard element shown in Figures 12, 13 and 14 are designated 50, 51 and 52 respectively.

The blade 50 is of the same form as blade 3 with this exception that it is not provided with the openings 22, 23, 24 and 25, but is formed with a pair of spaced parallel elongated oval-shaped slots 53, 54 disposed lengthwise thereof and extending from a point substantially at the transverse median of head part 55 to a point substantially at the transverse median of the arms 56, 57. Otherwise than that as stated, the blade 50 is constructed similar to blade 3. The keyhole-shaped opening, clearances, furcation and gripping part of blade 50 are designated 58, 59, 60 and 61 respectively.

The holder element 51 is constructed in the same manner as the element 4 with this exception that it is not provided with the lugs 31, 32, but in lieu thereof it is formed on its inner face with a pair of spaced parallel elongated oval-shaped ribs 62, 63 between the longitudinal median and side edges thereof. The ribs are of a length to have their ends arranged between the transverse median and the ends of element 51. The threaded 10 stem of the latter is designated 64.

The guard element 52 may be of the same cross sectional contour as elements 2 or 34, but element 52 is not provided with the sockets 13 or 41, but in lieu thereof is formed with a pair of spaced 15 parallel elongated oval-shaped sockets 65, 66 between the longitudinal median and side edges thereof. The sockets are of a length to have their ends arranged between the transverse median and each end of element 52. The central square opening in element 52 for the passage of stem 64 is 20 designated 68.

The slots 53, 54 align with sockets 65, 66 respectively when the blade 50 is mounted upon element 52. The ribs 62, 63 are to pass through slots 53, 25 54 respectively and seat in the sockets 65, 66 respectively when the holder element 51 is mounted upon blade 50. The ribs 62, 63 coact with the slots 53, 54 and sockets 65, 66 to provide the same function as the coacting of the lugs 31, 32 with the openings 22, 23, 24, 25 and sockets 13 or the coaction of the lugs 48 with the openings 43, 44, 45, 46 and sockets 41. Such function 30 prevents a portion or portions of the blade shifting or the bodily shifting of the blade as an entirety 35 relative to the other elements of the razor when

the latter is used, as well as functioning to reinforce the head part and arms of the blade.

What I claim is:—

In a safety razor, a handle formed with a socket for a part of its length, said socket of two different diameters, the portion of smallest diameter being threaded, the portion of largest diameter opening at the forward end of the handle, a guard formed with a centrally arranged polygonal shaped opening and lengthwise extending grooves 10 adjacent its side edges, a holder having an integral stem formed of a polygonal shaped forward part having a pair of spaced side faces parallel to the edges of the holder and extending through said opening and into said portion of largest diameter, said stem having a reduced peripherally threaded rear part engaging with the aforesaid threaded socket portion, a reversible blade positioned between the holder and guard, said blade being formed with a lengthwise furcation for inserting it in position from corresponding ends of said holder and guard, said furcation having parallel side walls for contacting said pair of spaced side faces for guiding the blade during its lengthwise insertion between the holder and guard, 15 opening at one end of and having its base disposed between the transverse median and the other end of the blade, said base opposing in close relation another side face of the said forward part, and said holder, guard and blade having coacting interengaging blade positioning means disposed inwardly adjacent respectively to the side edges of the holder, to the grooves of the guard and to the side edges of the blade.

FRANK F. SCHLATTAU. 35
